UNITED STATES PATENT OFFICE

CALVIN WURZLOW, OF HOUma, LOUISIANA

GARBAGE RECEPTACLE

Application filed May 10, 1927. Serial No. 190,248.

This invention relates to a garbage receptacle, and has for its primary object the construction of an apparatus of this character incorporating a novel construction of closure 5 that may be readily arranged in place but locked against removal under predetermined conditions.

An object of the invention is the construction of a garbage receptacle with an 10 open top, below which is arranged a special construction of closure that is arranged in place or removed in a novel manner.

Another object of the invention is the construction of a closure that is capable of 15 horizontal movement into the receptacle for positioning within the receptacle by a gravitational action.

A feature of the invention is the combination of a novel form of closure with a novel 20 construction of locking device coacting with a novel construction of receptacle in a manner that the closure is effectively held in place at all times.

With these and other objects in view, my 25 invention will be better understood from a description of the same when taken in connection with the accompanying drawings, wherein:—

Figure 1 is a front elevation of a garbage 30 receptacle constructed in accordance with my invention;

Figure 2 is a vertical sectional view on the line 2—2 of Figure 1;

Figure 3 is an enlarged cross sectional 35 view;

Figure 4 is a sectional view on the line 4—4 of Figure 2;

Figure 5 is a plan view of another form 40 of closure;

Figure 6 is a side elevation of that form of 45 closure shown in Figure 5.

Again referring to the drawings illustrating two of the many constructions of my invention and more particularly to Figures 1 to 4 inclusive, the numeral 1 designates a receiver having an open top 2 and provided with a base 3 so that the bottom 4 may be spaced from the ground to preserve the same.

As it may be advisable to form the receptacle out of wood, I have illustrated a metallic

liner 5. The front wall 6 of the receiver is provided with a slot 7 of rectangular configuration to provide the bottom wall 8, end wall 9, and top wall 10 which is cut away to provide the intercommunicating recess 11.

Secured to the interior surface of the receiver at a predetermined distance below the bottom wall 8 is a frame 12 forming a support for my novel construction of closure 13. The closure 13, which is of the proper configuration to be snugly received within and close the receiver, is provided with a recess in its under side to provide a shoulder and an extension 14 overlapping the bottom wall 8 and provided with a hand grip 15.

Referring to Figure 2, it will be noted that when the closure is passed through the slot 7 and is brought to rest upon the frame 12, the receiver is effectively closed with the extension 14 resting on the wall 8 and the said shoulder resting in engagement with the inner side of the front wall 6 to prevent removal of the closure by a horizontal movement. To remove the closure, it is necessary to incline the closure in a vertical direction 75 a predetermined degree to allow the closure to ride over the wall 8, and to prevent this action under certain conditions I provide a novel construction of lock device 16 that is of a design to have abutting relation with 80 a portion of the receiver to prevent removal of the closure.

In one of its constructions, this device is in the form of a bar 17 mounted for sliding movement on the upper surface of the closure 85 so that when the latter is to be removed the bar may be moved into registration with the recess 11 so as to pass therethrough in the removal of the closure, but when the device is in any other position the same will have 90 abutting relation with the interior surface of the receiver so as to prevent removal of the closure, as clearly illustrated in Figure 1. It is, of course, to be understood that this bar may be connected in any suitable manner 95 to the closure to have its required movement, but I have found it of advantage to provide the bar with a rib 18 movable in a slot 19 formed in the closure and locking therewith through the use of a plate 20 slidably mounted 100

in the guide grooves 21 laterally disposed with relation to the slot. As the slot and grooves open out at the sides of the cover, it will be appreciated that the bar may be 5 very readily brought into interlocking engagement with the cover and may slide approximately the entire width of the closure.

In Figures 5 and 6, I have illustrated another form of locking device of a simplified 10 construction, consisting solely of a bar 22 adjustably connected to the closure in any suitable manner but preferably by a pivot element 23 so that the bar may be thrown into various angular positions for alignment 15 with the recess or out of alignment therewith. In this particular case, the closure 24 is also provided with a hand grip 25.

From the foregoing description taken in connection with the accompanying drawings, 20 it will be apparent that I have provided a novel construction of garbage receptacle in which the various parts are so designed and associated that the cover may be more effectively associated with the receptacle or receiver and may be readily removed or locked in closed position. It will also be appreciated that the closure can be completely removed by a lateral horizontal movement so as not to be soiled or contaminated in the passage of 25 garbage through the open top of the receiver.

It is, of course, to be understood that the cover and receiver may be constructed and designed in various other manners than illustrated and other suitable forms of locking device may be associated with the closure and, therefore, I do not desire to be limited in any respect except as set forth in the following claims.

I claim:

40. 1. A garbage receptacle comprising a receiver having an open top and a slot in one wall thereof, the slot having a recess in one wall, a closure insertible through said slot to be positioned within the receiver, and a lock 45 device having sliding connection with the closure and movable into and out of position to register with the recess.

2. A garbage receptacle comprising a receiver having an open top and a slot in one 50 wall thereof, one wall of the slot having a recess therein, a closure insertible through the slot and having abutting relation with the inner surface of the said wall of the receiver, and a lock device slidably associated with 55 the closure and adjustable to assume a position to pass through said recess and a position to one side of the recess for abutting engagement with the said wall of the receiver.

3. A garbage receptacle comprising a 60 receiver having an open top, one wall of the recess having a slot and the upper wall of the slot having a recess, a support mounted in the receiver in a plane below said slot, a closure insertible through the slot to rest upon 65 said support, and a bar slidably mounted on

the closure, the closure having a groove therein, and the bar having a portion slidably fitting in the groove in the closure so as to be movable to positions in alignment with or out of alignment with said recess to allow or prevent the removal of said closure through 70 said slot.

4. In a receptacle of the character described, a closure having a centrally extending slot and guide grooves communicating therewith, a bar slidably mounted on the closure with a rib arranged in said grooves, and a plate secured to the rib and mounted in said grooves to interlock said bar with the walls 75 of the slot.

5. In a receptacle of the character described, a closure having a centrally extending slot and guide grooves communicating therewith, a bar slidably mounted on the closure with a rib arranged in said grooves, 80 a plate secured to the rib and mounted in said grooves to interlock said bar with the walls of the slot, said closure being provided with an extension, and a hand grip secured to the 85 extension.

6. In combination, a receiver having a recess in the side wall thereof, a closure, and a bar slidably associated with the closure for movement into alignment with said recess to allow the removal of said closure.

7. A garbage receptacle comprising a receiver having an open top and a transversely extending slot in one of its walls, a support within the receiver in a plane below the slot, and a closure for insertion and removal through the slot and in its inserted position movable in a horizontal plane for abutting the wall of the receiver below said slot and resting upon said support.

8. A garbage receptacle comprising a receiver having an open top and provided in one wall with a transversely extending slot, a frame mounted within the receiver in a plane below the slot, a closure insertible through the slot and disposable upon said frame, and a locking device upon the closure adjustable in a horizontal plane to abut the said wall of the receiver in tilting of the closure toward withdrawal position.

In testimony whereof I affix my signature.

CALVIN WURZLOW.
